PRINTING MACHINE

Walter T. Gollwitzer, Chicago, Ill., assignor to
Addressograph Company, Wilmington, Del., a
corporation of Delaware

Application December 18, 1930
Serial No. 503,160

5 Claims. (Cl. 101—58)

This invention relates to printing machines and more especially to a selector for such machines of the character through which variable printing devices are sequentially passed from which printing impressions are made.

The salient object of my invention is to provide a novel selector for determining whether or not impressions are to be made from the printing devices passed through the machine. The selection or determination of the printing devices is usually controlled by suitable means on the printing devices such as removable tabs, notches, openings, or the like. However, the size of the printing devices is usually limited and the number of such determining means that can be provided is consequently limited. In the art, each of such means is known as a primary selection and the selection may be determined from any one of these means or from a group of such means. However, group selections are of course dependent upon the number of primary selections, and it is therefore an important object of my invention to provide a selector having a large number of primary selections.

A further object is to provide a selector which may be readily associated with any of the various types of printing machines already in use or in newly constructed machines.

A still further object is to arrange the determining means on removable tabs in such a manner that a plurality of selections may be arranged on each tab.

In the selected embodiment of the invention illustrated in the accompanying drawings

Fig. 1 is a fragmentary side view of a printing machine embodying my invention and in which some parts are broken away;

Fig. 2 is a longitudinal sectional view of the machine as illustrated in Fig. 1;

Fig. 3 is a longitudinal sectional detail view, drawn to an enlarged scale, showing the detecting portions of my improved selector mechanism;

Fig. 4 is a fragmentary plan view of the machine in which certain parts are broken away;

Fig. 5 is a transverse sectional view taken substantially on the line 5—5 on Fig. 4;

Fig. 6 is an elevational view of one of the printing devices employed in the machine; and

Figs. 7, 8, 9, and 10 are perspective views of the removable tabs employed in the device.

In the accompanying drawings I have fragmentarily illustrated a printing machine which may be, for example, of the character disclosed in my co-pending application, Serial No. 451,812, filed May 12, 1930. The machine as disclosed in that application and in the accompanying drawings includes a frame 11 in which the main drive rocker 12 is pivotally mounted at 13. A reciprocal movement is imparted to this main

drive rocker 12, which, in turn, is transmitted through the link 14 to the printing device feed arrangements including the rocker 15 pivotally mounted on the frame at 16, the link 14 being pivotally connected to the main drive rocker 12 at 17 and to the rocker 15 at 18. The printing devices D are introduced into a magazine M and are successively withdrawn therefrom and passed along the printing device guideway 19 by the pawls 20 suitably mounted on the printing device feed slide bar 21. An arm 22 depends from the frame 11 and pivotally mounted thereon is a rocker 23 connected through a link 24 to the slide bar 21. The rocker 23 is connected through a link 25 to the rocker 15 and therefore when the main drive rocker 12 is reciprocated, movement is transmitted to the bar 21 to impart a step-by-step movement to the printing devices D so that the printing devices will move through selecting position in the machine wherein the printing device D' is shown and into printing position above the anvil 26 wherein the printing device D² is shown.

Pivotally mounted on the frame 11 in alignment with the pivotal mounting 16 of the rocker 15 is a stamper arm 27, at the outer end of which the platen P is adjustably mounted. The stamper arm includes a depending arm 28 having a roller 29 rotatably mounted at the lower end thereof that is movable in the channel 30 at the lower end of the rocker 31 pivotally mounted on the same center as the pivotal mounting 13 for the drive rocker 12. On the rocker 31 is a pad 32 against which the end of a pawl 33 is normally abutted, the pawl 33 being pivotally mounted on the main drive rocker 12 at 34. As described in my referred to co-pending application the main drive rocker includes a portion which extends behind the pad 32 and which engages the same during each reciprocation of the rocker 12 to urge the rocker 31 into the position illustrated in Fig. 2, this occurring when the main drive rocker 12 moves in a counter-clockwise direction, as viewed in Fig. 2. When, however, the main drive rocker 12 is moved in a clockwise direction, as viewed in Fig. 2, the pawl 33 engages the pad 32 and imparts movement to the rocker 31 and therefore the channel 30, which is in the nature of a cam groove and acts on the roller 29 to move the depending arm 28 and consequently the stamper arm 27 to move the platen P toward the anvil 26, and an impression is made from the printing device D² through a suitable ink ribbon (not shown). It is therefore manifest that downward or printing movement of the platen P depends upon the engagement of the pawl with the pad 32, and the selector mechanism forming the subject matter of this invention controls the engagement of the pawl with the pad.

In the upper surface of the pawl 33 there is a recess 35 and at one end of this recess a shoulder 36 is defined. Journaled in the main frame 11 is a shaft 37 having an arm 38 thereon carrying a roller 39 which may be disposed in the recess 35, as illustrated in Figs. 1 and 2, when the pawl 33 engages the pad 32, but when the roller 39 moves onto the shoulder 36 the pawl 33 is pivoted about the pivotal mounting 34 thereof against the action of the spring 40 and is disposed out of the path of the pad 32. Also fixed on the shaft 37 is a bell crank including an arm 41 and an arm 42. The spring 43 is connected to the arm 42 and to a spring anchor on the frame 11, and this spring acts on the bell crank to urge the arm 41 in counter-clockwise direction as viewed in Fig. 1. Movement of the arm 41 is limited by engagement thereof with a pin 42 on the arm 43 of the rocker, generally indicated by 44, pivotally mounted at 45 on the bracket 46. Also mounted on the bracket 46 is the rocking member 47 having plates 48 and 49 thereon between which a recess 50 is defined. Adjacent the rocking member 47 is an arm 51 having a recess 52 therein and a shoulder 54 is defined at one end of the recess 53. One end of the rod 55 is movable into the recess 53 or onto the shoulder 54 and when disposed on the shoulder 54 the rocking member 47, which is connected to the arm 51 through the spring 56, is disposed in the position illustrated in Fig. 2. Pivotally mounted at 57 on the rocker 15 is a pawl 58 having a nose 59 engageable with the plate 60 on the arm 61 of the rocker 44. When the rocker 15 is moved in the manner previously described the nose 59 of the pawl 58 engages the plate 60 and pivots the rocker 44 to move the pin 42 upwardly from the position illustrated in Fig. 1 so that said pin will be disposed out of the recess 50. In a manner to be described the rocking member 47 is positioned so that either the plate 48 or 49 or the recess 50 will be positioned below the pin 42 after movement thereof out of the recess 50. When the nose 59 disengages the plate 60 the rocker 44 pivots in a clockwise direction and the pin 42 moves downwardly. Should the pin 42 move into the recess 50 the arm 41 will move downwardly and the roller 39 will be disposed in the recess 35. However, should the pin 42 come to rest on either the plate 48 or the plate 49, the arm 41 will be held in an upper position and the roller 39 will be disposed on the shoulder 36 and the pawl 33 will not engage the plate 32 and consequently no movement will be imparted to the rocker 31. On the rocker 15 there is a pawl 62, the nose of which is engageable with a plate 63 on the rocker 64 pivotally mounted on the shaft 65 journaled in the frame 11. Also mounted on the shaft 65 and on the shaft 65' is the selector bar structure 66 and a spring 67 is interposed between the structure 66 and the rocker 64. A plate 68 carried by the bar 70 is movable downwardly in a certain amount to be described presently and engages the upper end of the rod 55 to move the same and thereby position the rocking member 47 as previously described. The selector bar structure carries the bar 70 in which a plurality of transversely and longitudinally aligned openings are provided into which pins 71 may be introduced when the removable plate 72 (Figs. 3 and 4) is removed. The positioning of the pins 71 in certain of the openings in the bar 70 will be described more fully presently. Disposed below the plane of the plate guideway 19 is a block 73 which has a

plurality of transversely and longitudinally aligned openings therein positioned correspondingly to the openings in the bar 70.

The printing device D' in selecting position has detachable tabs T connected along one edge thereof, which tabs may be held in a position in the manner set forth in the patent of H. E. Hubbard, No. 1,677,449, patented July 17, 1928. The tabs T are illustrated in detail in Figs. 7 to 10, inclusive, and these tabs include body portions which project beyond the edge of the printing device when the tabs are installed in position, this being clearly illustrated in Fig. 6. On these tabs the detecting means are in the form of embossages or protuberances. These protuberances are, in the present instance, embossed at any of four different positions on the body portions of the tabs. In Fig. 7 the protuberance A is embossed on the body portion of the tab T adjacent the upper right hand corner thereof. In Fig. 8 the protuberance B is shown on the body portion of the tab adjacent the upper left hand corner thereof. In Fig. 9 the protuberance C is shown on the body portion of the tab adjacent the lower right hand corner thereof. And in Fig. 10 the protuberance D is shown on the body portion of the tab adjacent the lower left hand corner thereof. The determination of the selection results from the disposition of the embossages or protuberances A, B, C, and D on the tabs T, which tabs T in turn are disposed at various positions along the edge of the printing device. In the present embodiment of the invention the printing device is arranged to have twelve such tabs T secured thereto and since each of the tabs may be provided with an embossage at any of four different positions it is manifest that I am enabled to thereby attain forty-eight primary selections. However, under certain conditions the printing devices may be arranged to have additional tabs T thereon, and the tabs may be provided with a greater or a less number of protuberances, so it is to be understood that my invention is not limited to the use of four protuberances and twelve tabs, this merely being exemplary of the invention.

It has been pointed out that the pins 71 are arranged in two rows in transverse and in longitudinal alignment. The pins 71 in one transverse row will be aligned with the protuberances positioned similarly to the protuberances A and B, while the pins in the other transverse row will be aligned with protuberances positioned similarly to the protuberances C and D. The spacing apart of the pins in the two rows just described corresponds to the spacing apart of the protuberances A and B, and C and D, and since, for example, the protuberances A and C, and B and D will be in alignment on the tabs, it is manifest that the pins 71 will be similarly aligned.

An example of use of the device may be that a tab T might be positioned as indicated by 74 in Fig. 6 with a protuberance A thereon. If only printing devices having a tab at such a position with a protuberance A thereon were to be printed, for example, a pin 71 would be disposed at this position. Therefore, when the main drive rocker 12 is set in motion and movement is imparted to the rocker 15, the rocker 64 will be moved which will move the structure 66 downwardly, this movement being transmitted through the spring 67 and if the printing device D' has a tab at 74 thereon with a protuber-

ance A, the pin 71 will strike this protuberance and will hold the bar 70 against movement and therefore the plate 69 will not move the plate 68, and thus the pin 42 will move into the recess 50 to consequently allow the pawl 33 to engage the pad 32 and thus the platen P will be moved downwardly to make an impression from the printing device D', which will have moved from selecting position into printing position above the anvil 26 after it has been engaged by the pin 71 to determine the selection. If there is no tab T at the position 74 having a protuberance A thereon, the pin 71 will manifestly not strike such a protuberance and therefore the bar 70 will move in an amount greater than the first movement, and the plate 69 will act on the plate 68 which will engage the rod 55 and move the same downwardly and in the present instance the plate 48 will be disposed below the pin 42 which will be held in an upper position and therefore the pawl 33 will not engage the pad 32 and thus no movement will be imparted to the platen P.

An example of a group selection may be that a printing device having tabs positioned as indicated in Fig. 6 might be used and only printing devices having tabs and protuberances as illustrated in Fig. 6 will be printed. I have stated that the positions A, B, C, and D of the protuberances indicate the primary selections, but it is manifest that a tab might be provided with more than one protuberance which, in itself, would constitute a group. Such a tab is indicated in the position 75 in Fig. 6, and this tab T has protuberances B and C thereon. When printing devices such as those illustrated in Fig. 6 are to be printed with the machine arranged as previously described, the pins 71 will be disposed to correspond to the positions of the protuberances on the tabs at the positions illustrated. Therefore, when these pins strike these protuberances a printing operation will be performed as previously described. Should these pins fail to strike the protuberances the printing device will be skipped.

In the foregoing description I have described a selection as being performed to print printing devices tabbed only in a certain manner, but as is well understood in the art this arrangement might be reversed and printing devices tabbed in a certain manner would be skipped, while all others would be printed,

In the foregoing description I have described a selected embodiment of my invention but it is to be understood that this is capable of variation and modification and I therefore do not wish to be limited to the precise details set forth but desire to avail myself of such changes and alterations as fall within the purview of the following claims:

I claim:

1. In a printing machine, means sequentially moving printing devices therethrough, the printing devices having tabs engaged therewith at predetermined places, said tabs embodying predetermined positions whereat embossages may be formed, an operating part in the printing machine, a selector for controlling the operation of said operating part and including a selector bar having a plurality of transversely and longitudinally aligned rows of openings therein positioned correspondingly to the predetermined positions on said tabs whereby pins may be

mounted in selected openings for cooperation with the predetermined positions on said tabs to determine the operation of said selector.

2. In a printing machine including an operating part, and means for feeding printing devices through selector and printing positions in the machine, said printing devices having tabs secured at selected places along corresponding edges thereof, and said tabs having predetermined places whereat embossages may be formed, the combination of a selector mechanism for controlling the operation of said operating part and including a selector bar movable toward and away from the tabs on the printing device at selector position, said selector bar having a plurality of openings therein respectively aligned with the predetermined places whereat embossages may be formed on the tabs on the printing device at selector position, and pins mounted in said openings and adapted to cooperate with the predetermined places on said tabs to determine the operation of said selector mechanism.

3. In a printing machine, means sequentially moving printing devices therethrough, said printing devices including tabs engaged therewith at predetermined places, said tabs having protuberances on the face thereof at selected predetermined positions, a platen, a selector controlling the operation of said platen and including a selector bar having a plurality of rows of openings therein positioned correspondingly to the predetermined positions on said tabs whereby pins mounted in selected openings for cooperation with protuberances at selected predetermined positions determine operation of said selector.

4. In a printing machine which has a platen for making impressions from printing devices fed into printing position in the machine, and means for feeding printing devices which have tabs secured at selected places along corresponding edges thereof and which tabs have embossages thereon at predetermined places, the combination of a selector mechanism for controlling the operation of the platen and including a selector bar movable toward and away from the tabs on the printing devices, said selector bar having a plurality of transversely and longitudinally aligned openings therein, and pins mounted in said openings and adapted to cooperate with the embossages on said tabs to determine the operation of said selector mechanism.

5. In a printing machine which has a platen for making impressions from printing devices fed into printing position in the machine, and means for feeding printing devices which have tabs secured at selected places along corresponding edges thereof and which tabs have embossages thereon at predetermined places, the combination of a selector mechanism for controlling the operation of the platen and including a selector bar movable toward and away from the tabs on the printing devices, said selector bar having two rows of openings therein in side by side relation with each opening in one row aligned with an opening in the other row, and pins mounted in selected openings and adapted to cooperate with the embossages on the tabs to determine the operation of said selector mechanism.

WALTER T. GOLLWITZER.
